[57] CLAIM

The ornamental design for an automatic filling coffee maker, as shown and described.

DESCRIPTION

FIG. 1 is a top, front and left side perspective view of an automatic filling coffee maker showing my new design; FIG. 2 is a left side elevational view thereof; FIG. 3 is a right side elevational view thereof; FIG. 4 is a rear elevational view thereof; FIG. 5 is a front elevational view thereof; FIG. 6 is a top plan view thereof; and, FIG. 7 is a bottom view thereof. The electric cord and water line in FIGS. 1, 2, 3, 4, 6, and 7 are shown broken away for ease of illustration.

FIG. 1

FIG. 2

FIG. 3

FIG. 4

FIG. 5

FIG. 6

FIG. 7
